UNITED STATES PATENT OFFICE.

DUDLEY T. FISHER, JR., OF COLUMBUS, OHIO.

DESIGN FOR A BARBER'S SIGN.

Application filed September 30, 1926. Serial No. 19,211. Term of patent 7 years.

To all whom it may concern:

Be it known that I, DUDLEY T. FISHER, Jr., a citizen of the United States, residing at Columbus, in the county of Franklin and the State of Ohio, have invented a new, original, and ornamental Design for Barber's Sign, of which the following is a specification, reference being had to the accompanying drawing, forming parts thereof.

The figure is a side elevation of a barber's sign showing my new design. As the design is commercially used, it is stamped from thin sheet metal, approximately $\frac{1}{16}$ inch in thickness.

I claim:

The ornamental design for a barber's sign, as shown.

DUDLEY T. FISHER, Jr.
